UNITED STATES PATENT OFFICE.

FRED MASON MARTIN, OF NEW YORK, N. Y., ASSIGNOR TO AMERICAN SMELTING
AND REFINING COMPANY, OF NEW YORK, N. Y., A CORPORATION OF NEW
JERSEY.

ORE-STREAM CONVEYER.

Original application filed September 11, 1920, Serial No. 409,587. Divided and this application filed April 28, 1922, Serial No. 557,106.

To all whom it may concern:

Be it known that I, FRED MASON MARTIN, a citizen of the United States, and resident of New York city, in the county of Kings and State of New York, have invented certain new and useful Improvements in Ore-Stream Conveyers, of which the following is a specification.

This invention relates to ore stream conveyers for use in handling ores and the like.

The invention has particular reference to conveying means of the belt type, suitable for handling sticky, slimy material of relatively great weight, in large quantities to expedite the work. It is especially well adapted for use in connection with ore handling machinery and ore sampling apparatus of the type shown in my copending application, Serial No. 287,137 filed April 3, 1919, and the divisional applications, Serial Nos. 333,892 filed October 28, 1919, and 409,587 filed September 11, 1920, of which latter application this is a division.

An object of the invention is to effectually prevent side creep of the belt, and minimize tension of the material of which the belt is formed, thus lengthening the useful life of the belt.

Another object of the invention herein disclosed is to provide a stream forming device of rugged construction to withstand the hard working conditions to which heavy ore handling machines are usually subjected and at the same time to provide a machine which can be operated economically and independently of the character of material handled.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

Figure 1 is an enlarged view of the material receiving hopper element of a machine constituting a preferred embodiment of my

complete invention and with parts of the hopper broken away to show internal construction;

Figure 2 is an enlarged view in right end elevation of the device shown in Figure 1 and with parts broken away;

Figure 3 is an enlarged view of the driving mechanism of Figure 1; and

Figure 4 is a vertical sectional view taken on the line 4—4 of Figure 1.

In the drawings there is shown a suitable supporting framework upon which is mounted a fixed open-top hopper 16 adapted to receive the material to be treated. The material in the hopper is moved by a belt conveyor 17 defining the bottom of the hopper across the hopper thereof, is discharged therefrom and is permitted to fall freely into engagement with a disintegrating device 18 which acts on the material to break up the stream discharged from the hopper. The broken-up stream is then permitted to fall onto a sampler or other treating device more particularly defined in the parent application above identified.

It will be noted that the receiving end of the hopper is provided with a pair of oppositely disposed, downwardly and inwardly inclined deflectors 23 which act to distribute the material discharged into the same and to dispose the same evenly on opposite sides of the longitudinal medial line through the hopper. Each of the deflectors is pivotally connected to the adjacent side of the hopper at its upper edge. The deflectors are each held in adjusted swinging position by means of a lifting rod 24 which passes through the adjacent side and is held in set position by nuts 25 as shown in Figure 2. The hopper is provided at its discharge end with an opening 26 having a width equal to that of the hopper but relatively small in its vertical dimension as shown in Figure 2. A plow 27 is mounted in the opening 26. A pair of transverse bars 28 constitute internal braces for the hopper and add strength and rigidity to the structure. Vertically adjustable hanging rods 29 connect the bars 28 with the advance edge and with opposite sides of the plow. By this construction the bottom edge

of the plow may be set at a desired distance above the conveyer 17 and thus a stream of material of predetermined cross section may be delivered through the opening 26 to the 5 disintegrator 18.

The belt conveyer 17 includes an endless material-receiving belt 30, the upper run of which fits relatively close to the open bottom of the hopper as shown in Figure 4 10 and constitutes a movable bottom for said hopper. This belt is relatively wide and extends beyond the lateral sides of the hopper so as to minimize any tendency of leakage between the hopper and the conveyer. The 15 belt encircles an endless driving frame 31, and has its upper run resting on the frame and held thereto frictionally but is otherwise unsecured to the frame. A plurality of longitudinally, extending tracks, in Figure 20 4 shown to be four in number, extend parallel to the length of the hopper with the two inside tracks 32 positioned below the hopper and the two outside tracks 33 offset laterally to the outside of the hopper. The 25 frame includes a series of transversely disposed bars 34 connected at their outer ends by roller chains 35. The frame is designed to engage and slide on the tracks through roller casters 36. The chains of the frame 30 are passed about end sprocket wheels, one set of which, 37, at the discharging end of the conveyer constitutes driving sprockets and is mounted upon and driven from a power shaft 38. The other set of sprockets 35 39 is carried by a shaft 40 mounted in take-up bearings 41 by means of which the tension on the conveyer frame is adjusted. The loads which are discharged on to the belt adjacent the center thereof tend to depress the central medial line of the belt and thus 40 acts to center the belt on the frame. In this way the belt is held with its opposite edges adjacent the open bottom of the hopper and in spaced relation to the end 45 sprockets engaging the roller chains 35. In this way when the frame is carried from its horizontal path into its path around the sprocket wheels, the belt 30 is moved clear of the sprocket wheels thus permitting the 50 use of a belt of unusual width.

The intermediate tracks 32 form supports for rollers 42 each pivotally supported upon a pair of depending brackets 43 secured to a slat 31 opposite the respective track. It 55 will be understood that each slat may be provided with such rollers corresponding in number to the number of tracks provided. The tracks may extend only in position to be engaged by such rollers as are in the upper horizontal plane of movement of the belt, and their ends may be rounded off as clearly shown in Figure 1 to minimize vibration. Thus the rollers ride freely while in the lower part of the orbit of movement, 60 and are in position to engage the tracks 65

again when brought into contact with the incoming end thereof.

In operation and assuming that the several movable elements of the device are operatively connected to the power system 70 so as to cause them to operate at the desired relative speed and assuming that load after load of the material is dumped into the hopper, the device can be left by itself and will operate automatically. 75

The deflectors on opposite sides of the hopper tend to distribute the incoming loads of material on opposite sides of the medial line through the nose of the plow and as the material is carried by the belt conveyer into engagement with the plow it will be caused to spread out in a layer of uniform thickness and the conveyer will discharge the same uniformly through the outlet opening 26. As the layer of material is fed to the disintegrator, it is cut into longitudinal strips by means of the cutting disks, and the disintegrating wires moving upwardly through the mass, usually at relatively high speed, will tend to break up the strips before the material is permitted to fall towards the sampler. Even if wet and sticky the material is separated and falls in a stream of separate particles. 90

By means of a device of the character 95 thus outlined it is possible to obtain a fair sample of the material, even though this material be of a plastic nature and otherwise difficult to handle. Using a relatively large belt on the conveyer gives the feeder a large 100 capacity at slow speed. Further, with the particular type of conveyer disclosed lateral or side creep of the belt is minimized and belt tension is eliminated as the driving or carrying effect is proportioned to the weight of the load only and relative movement between the belt and its carrying frame is minimized so as to eliminate wear on the underside of the belt. 105

While I have shown and described and have pointed out in the annexed claims certain novel features of my invention, it will be understood that various omissions, substitutions and changes in the form and details of the device illustrated and in its operation may be made by those skilled in the art without departing from the spirit of my invention. 110

Having thus described my invention, I 115 claim:

1. In a device of the class described, the combination of an open bottom hopper, a plurality of parallel stationary tracks positioned below said hopper, a conveyer including a continuous belt encircling said tracks lengthwise thereof, extending transversely across the tracks and constituting the bottom of the hopper, a belt-supporting 120 endless frame encircled by the belt, said frame provided with wheels adapted to move 125

on said tracks to support the upper run of the belt and means for driving said endless frame.

2. In a device of the class described, the combination of an open bottom hopper, a stationary track positioned below said hopper, a conveyer including a continuous belt encircling said track and constituting the bottom of the hopper, a belt-supporting endless frame encircled by the belt and adapted to hold the belt in position substantially to close the bottom of the hopper, said frame including a plurality of transversely extending slats providing rigidity to the frame transversely of its direction of travel while permitting a flexibility longitudinally of the direction of travel. 45

3. In a device of the class described, the combination of an open bottom hopper, a plurality of stationary tracks positioned below said hopper, a conveyer including an endless belt with its upper run constituting the bottom of said hopper and having a width greater than the width of said open bottom, an endless belt supporting frame encircled by said belt and supporting the upper run of the same, a sprocket wheel for driving said frame and spacing means carried by the frame and engaging the tracks for maintaining the wide belt adjacent the hopper. 50

4. In a device of the class described, the combination of an open bottom hopper, an endless belt constituting a moving bottom for the hopper and an endless frame operatively connected to the bottom for moving the bottom and holding the same in a fixed plane close to the open bottom of the hopper. 55

5. In a device of the class described, the combination of an open bottom hopper, a plurality of parallel tracks positioned below the hopper, the two outside tracks being

offset laterally to the outside of the hopper, a flexible endless frame including transverse strengthening members supported by said tracks, means for moving the frame with its upper reach supported from the tracks and an endless belt having a width sufficient to extend across the open bottom of the hopper, positioned on the upper reach of the frame and moved thereby across the 50 open bottom of the hopper. 45

6. In a device of the class described, the combination of a track having down-turned ends, a frame encircling the track lengthwise thereof, said frame provided on its inner side with rollers for engaging the track as the frame moves along the track, means for driving the frame and an endless belt encircling the frame and moved thereby. 55

7. In a conveyer, the combination of a track, an endless frame encircling the track lengthwise and including a plurality of inwardly extending brackets, rollers carried by the brackets for engaging the track as the upper reach of the frame moves along the track and an endless belt resting on the frame and moved by its frictional engagement therewith. 60 65

8. In a device of the class described, the combination of a pair of sprockets, a pair of parallel chains engaging said sprockets, longitudinally spaced apart slats extending transversely of the chains and connecting the same, an endless belt loose on said slats and moved thereby and means for driving one of the sprockets thereby to cause the belt to move. 70 75

Signed at Hollywood, in the county of Los Angeles, and State of California, this 21st day of April, A. D. 1922.

FRED MASON MARTIN.
